UNITED STATES PATENT OFFICE.

PETER C. HALL, OF SAYBROOK, ILLINOIS.

WATCHMAKER'S CABINET.

SPECIFICATION forming part of Letters Patent No. 727,938, dated May 12, 1903.

Application filed February 5, 1902. Serial No. 92,692. (No model.)

To all whom it may concern:

Be it known that I, PETER C. HALL, a citizen of the United States, residing at Saybrook, in the county of McLean and State of Illinois, have invented a new and useful Watchmaker's Cabinet, of which the following is a specification.

This invention relates to watchmakers' cabinets.

10 The object of the invention is to provide a drawer or receptacle of the character specified with means for retaining going-springs therein in coiled condition and in such manner that when the cover is opened as to permit application to the springs of a spring-gage to determine the size of spring required.

With these and other objects in view, as will appear as the nature of the invention is better understood, the same consists in the 20 novel construction and combination of parts of a drawer or receptacle for watchmakers' materials, as will be hereinafter fully described and claimed.

In the accompanying drawings, forming a 25 part of this specification, and in which like numerals of reference indicate corresponding parts, there is illustrated one form of embodiment of the invention capable of carrying the same into practical operation, it being understood that the elements therein exhibited may be varied or changed as to shape, proportion, and exact manner of assemblage without departing from the spirit of the invention.

30 In the drawings, Figure 1 is a view in perspective of a drawer or receptacle constructed in accordance with the present invention. Fig. 2 is a view in vertical longitudinal section through the same. Fig. 3 is a perspective detail view showing one manner in which 35 the compartments or partitions for holding the going-springs separated are associated with the receptacle. Fig. 4 is a similar view showing another manner of associating the partitions with the receptacle.

40 Referring to the drawings, 1 designates a drawer provided with suitable cleats 2 for engaging guides in a cabinet, as usual. The drawer is divided in this instance into four compartments 3, 4, 5, and 6 by transverse partitions 7, 8, and 9. The compartments are designed to contain going-springs of different sizes, the compartments 3 and 4 being adapt-

ed to hold springs for large American movements—say 16 and 18 size—and the compartment 5 to hold springs for small American 55 movements or for Swiss movements. The latter compartment is smaller in size than the other two and of less depth, the latter being effected by providing the said compartment with a false bottom 10. Each of the 60 compartments is divided into a plurality of smaller compartments by longitudinally-disposed partitions 11, those of the compartment 3 being held in position between vertical guides 12, as shown in Fig. 3, and those of the 65 compartment 4 by providing the said partitions with prongs or points 13, seated in openings in the partitions 7 and 8. The partitions of the compartment 5 may be held in place by either of the means above described, as 70 may be preferred, or all may be held in place in the same manner.

The compartments 3, 4, and 5 are closed by lids or covers 14, 15, and 16, suitably hinged, respectively, to one end of the drawer and 75 to the partitions 7 and 8, as clearly shown in Fig. 2. Each of the covers carries on its under side means for holding the uncoiled free ends of the going-springs detachably connected therewith when the covers are opened, 80 whereby to permit application of a spring-gage to determine the spring desired without necessitating its removal from the compartment. The holding means for each spring consists of a piece of metal having a base 17 85 secured to the under side of the lid, two side flanges 18 and an end flange 19, having an inturned terminal lip 20, which may occupy a plane parallel with the base 17, as shown, or be inclined toward the same, the terminal 90 20 constituting a catch for engaging the free ends of the springs, so that when the cover is open, as shown in Figs. 1 and 2, the spring will be held from disconnection therefrom and will be freely exposed to view, while the 95 side flanges will prevent the springs contained in one compartment from becoming entangled with those of another compartment. These holding means are so disposed and spaced apart as to form grooves to receive the upper edges of the partitions 11 when the lid or cover is closed, the depending flanges of the adjacent plates extending on opposite sides of the partitions. Each

cover has a suitable fastening device associated with it to hold it closed against stress of the springs, the device in this instance consisting of an ordinary turn-button 21 to engage a cleat 22, secured to the upper edge of the transverse partition. The compartment 6 may contain a plurality of holders 23 for containing wheels, jewels, &c., and the said compartment may be provided with a hinged cover, if desired. If desired, the upper edges of these partitions may be provided with numbers or with attached printed labels bearing the number and size of the springs contained in the compartment immediately opposite it, by which arrangement selection of the springs will be facilitated.

Having thus fully described my invention, what I claim as new, and desire to secure by Letters Patent, is—

20 1. A device of the class described comprising a holder provided with a cover, said cover having a plate on the under side thereof provided with depending spaced flanges forming a chamber to receive one end of a going-
25 spring and serving as stops to limit the lateral movement of the spring, and an inturned lip for engagement by the uncoiled free end of the going-spring.

2. A device of the class described comprising a holder provided with a compartment 30 having spaced upright partitions disposed therein, a cover for said compartment having flanged plates secured to the under side thereof, said plates being spaced apart with the flanges of adjacent plates adapted to extend 35 down on opposite sides of said partitions when the cover is in closed position, and means for detachably engaging the uncoiled free end of a going-spring.

3. A holder for watchmaker's material comprising a drawer provided with a plurality of compartments, covers for the compartments, and flanged plates secured to the under side of each of said covers to receive and limit the lateral movement of one end of a 40 going-spring and provided with holding devices for detachably engaging the uncoiled free end of the going-spring.

In testimony that I claim the foregoing as my own I have hereto affixed my signature in the presence of two witnesses.

PETER C. HALL.
